Primary Examiner — Kevin K Rudzinski*Assistant Examiner* — J. Thorn, Sr.(74) Attorney, Agent, or Firm — Compton & Associates PLLC; Matthew Compton(57) CLAIM

The ornamental design for a leather and elastic belt, as shown and described.

DESCRIPTION

FIG. 1 depicts a front view of a leather and elastic belt showing my new design;

FIG. 2 depicts a back view thereof; and,

FIG. 3 depicts a perspective view thereof.

The portion of the belt shown in short, dashed broken lines show environmental structures that form no part of the claimed design. Long broken lines show contour. The leather and elastic belt is shown with symbolic breaks in its length. The appearance of any portion of the article between the break lines forms no part of the claimed design. The leather portions and elastic portions of the leather and elastic belt are set forth in the reference legends in the figures.
